by Frank J. Schaeffer, Jr.
Attorney

UNITED STATES PATENT OFFICE.

HERBERT O. TOMLINSON, OF WHEATON, ILLINOIS.

SEMI-INDIRECT-LIGHTING DEVICE.

1,382,145.

Specification of Letters Patent. Patented June 21, 1921.

Application filed September 12, 1919. Serial No. 323,254.

To all whom it may concern:

Be it known that I, HERBERT O. TOMLINSON, a citizen of the United States, residing at Wheaton, in the county of DuPage and State of Illinois, have invented a new and useful Improvement in Semi-Indirect-Lighting Devices, of which the following is a specification.

This invention relates generally to electric-light fixtures and has for its object the provision of a fixture including a support or holder for an electric-light diffusing bowl or globe, which is simple in construction and ornamental in use.

Another object is to provide a fixture of this character with a holder which shall be largely concealed from view below and which shall effectively support the light diffusing bowl in a manner to afford ready removal of such bowl from the fixture without the disengagement of the holder from the shade.

With these and other objects in view, my invention consists in the novel construction, combination, and relative position of the parts and members hereinafter described and shown in the accompanying drawings, and particularly pointed out in the appended claims.

A structure embodying my invention is illustrated in the accompanying drawings, in which Figure 1, is an elevation showing my invention. Figs. 2 and 3 are respectively, side elevation and plan view of my improved bowl holder, and Fig. 4 is an enlarged detail in sectional view showing the attachment of the holder to the edge of the shade or reflector.

Referring to the illustrations, 10 indicates an incandescent electric lamp which is carried in the well known socket 11. A reflector or shade support 12, comprising a split ring 12^A encircling the socket 11 and having a binding screw 13 for clamping the ring to the socket, is provided with the outstanding annular flange 12^B with radially arranged screws 14 for releasably engaging the annular flange 15^A of the shade or reflector 15, which preferably is of white or opal glass. In this way the reflector is removable by downward disconnection from said supporting means therefor. I have preferred to show the reflector 15 of a flat downwardly flaring form.

The diffusing bowl 16, is preferably of translucent ground glass and may be of any

suitable shape or color. A suitable flange 16^A is formed around the upper edge of the bowl.

To support the bowl 16 below the reflector 15, I provide a support 17 which comprises preferably three downwardly diverging spring-like metal arms 17^A which are provided with hooked-ends 17^B adapted to engage any points on the flange 16^A to retain the bowl. The bowl is rotatable, of course, in these hooks, so that it can be inserted and removed in any rotatable position thereof. Near their upper ends 17^C the arms 17^A are held in spaced relation by a ring 17^D which is welded, or in any other way, attached to the arms. The ends 17^E are formed in a compound curve and are outwardly disposed in a manner to afford spring-like hooks which engage over the upper edge of the reflector and thus support the bowl therefrom.

It will be observed that the holder need not be disengaged from the reflector to permit the removal of the bowl, but that it is only required that one of the spring-arms 17^A be unhooked from the bowl flange to permit the bowl to be readily removed from the other two supporting arms. Also, by reason of the fastening means 13 the reflector and bowl and the supporting means therefor may be removed intact from the lower end of the socket. The lamp 10, it will be seen, permits the ring 12^A to be removed from the lower end of the socket, even when the lamp is in place, and if this is done the lamp can then be unscrewed, very obviously, after such removal of the bowl and reflector as a unit from the lower end of the socket.

It will be seen that the rigid ring 17^D fits snugly within the opening in the upper portion of the reflector 15, so that the upper end portions 17^E of the springy arms overhang the edge of said opening, whereby the bowl is firmly supported below the reflector. These springy upper end portions 17^E are sprung inwardly when forced upwardly through the opening in the reflector while the lower end portions 17^B are sprung outwardly to receive the annular upper edge of the bowl. Thus the bowl support is resiliently engageable with and detachable from the upper and inner edge of the reflector and is also resiliently engageable with and detachable from the rim or upper edge of the bowl, but the rigid ring 17^D holds the

springy or resilient arms 17^a in fixed relative positions, at points between their upper and lower ends, in the manner shown and described.

5. Of course, if the arms 17^a are too stiff, the longer and more flexible arms 17^a can be flexed or bent together to pass downwardly through the opening in the center of the reflector. In other words, the bowl-holder 10 can be inserted downwardly through the reflector, if for any reason it is not convenient or desirable to insert it upwardly. Thus the bowl-support or holder has resilient engagement with the bowl thus supported on 15 the reflector.

I claim:

1. A semi-indirect lighting device, comprising a socket to hold a lamp in depending position, a downwardly flaring reflector 20 supported on said socket, a translucent upwardly open diffusing bowl below said reflector to receive a lamp suspended from said socket, and having an outwardly extending flange at its top, a holder having a 25 plurality of flexible resilient arms adapted to detachably engage said flange to support said bowl, so that the bowl can be removed by springing one of said arms outwardly from said flange, and a rigid cylindric ring 30 to which the upper portions of said resilient arms are secured in spaced relative positions, the upper ends of said resilient arms being arranged to detachably engage the 35 inner edge of the reflector to support the bowl therefrom, so that the lower ends of said arms directly engage the bowl while their upper ends directly engage the reflector, substantially as shown and described.

2. The combination of an electric lamp, a 40 reflector, a light diffusing bowl below said reflector, a holder having a plurality of flexible resilient arms, said arms having hooked lower ends to detachably engage and support said bowl, so that the bowl can be 45 removed by springing one of said arms outwardly from said flange, the upper ends of said arms being curved to engage the inner edge of said reflector to support the bowl therefrom, so that the holder has a spring 50 grip directly on the reflector as well as on the bowl, and a rigid ring attached to said arms to retain portions thereof in spaced relation, substantially as shown and described.

55. 3. The combination of an electric lamp, a reflector, a light diffusing bowl below said reflector, a holder having a plurality of flexible resilient arms, said arms having hooked lower ends to detachably engage and support said bowl, so that the bowl can be 60 removed by springing one of said arms outwardly from said flange, the upper ends of said arms being curved and disposed upwardly and outwardly over the inner edge 65 of said reflector to support the bowl there-

from, so that the holder has a spring grip directly on the reflector as well as on the bowl, and a rigid ring attached to and near the top of said arms and below the plane of the inner edge of said reflector, substantially 70 as shown and described.

4. In an electric light, the combination of a support, a reflector having a central opening, a bowl below the reflector, and a bowl support having engagement with and 75 disengagement from the edge of said opening, and having rigidly connected spring gripping means for providing resilient engagement with and disengagement from the rim of said bowl, so that the bowl support 80 has a spring grip on the bowl thus supported by the reflector, means for supporting said reflector on said support, whereby the bowl holder can be forcibly pulled downward from the reflector, and so that the bowl 85 can be disengaged from the bowl holder without disengaging the latter from the reflector, and clamping means whereby the reflector and the supporting means therefor are removable intact from the lowermost 90 end of said support.

5. A structure as specified in claim 4, said bowl holder comprising a plurality of springy and upwardly converging arms forming said gripping means, and a rigid 95 ring rigidly connecting said arms in fixed spaced relation at a point between their upper and lower ends, so that the upper ends of said arms are forced inward when inserted in or removed from the reflector, whereby the lower ends of said arms are forced outward when the bowl is inserted or removed, said ring fitting snugly within and being adapted to pass up and down through said opening in the reflector 100 to permit the lower ends of said arms to pass through said opening, if desired, in the assembling of the bowl and reflector.

6. In a lighting device, the combination of a socket, a reflector having a central 110 opening, a support insertible downwardly through the reflector to engage the edge of said opening, a bowl below the reflector, and means on said support to detachably engage the upper edge of said bowl, so that the 115 bowl is rotatable in said means and is supported by the reflector, in combination with clamping means whereby the supporting means for both the reflector and bowl are removable intact from the lower end of the 120 socket.

7. A structure as specified in claim 6, said means being resilient arms which are flexible toward each other at their lower ends to pass through said opening and to engage and disengage said bowl.

8. In combination with an electric light bulb socket, a reflector and a light diffusing bowl, and means for supporting the reflector and bowl on the socket, comprising spring 130

gripping arms to engage the upper end of the bowl, so that said bowl can be removed by springing one of said arms outwardly, and rigid means to hold the upper portions 5 of said arms in fixed relation to each other, so that said arms are rigidly connected together when supported in operative position, said reflector having a central opening, and said arms thus rigidly united being adapted to be flexed to pass through said opening, to permit assembling of the reflector and bowl on the socket, so that said bowl can be removed by springing one of said arms outwardly, in combination with 10 clamping means whereby the supporting means for both the reflector and the bowl are removable intact from the lower end of the socket.

9. In a lamp, the combination of a reflector having a central opening, a light diffusing bowl, and a rigid support having downwardly extending spring arms rigidly and permanently united therewith and adapted to be flexed to pass through said 15 opening to grip the bowl, so that said bowl can be removed by springing one of said arms outwardly, in combination with clamping means whereby the supporting means for both the reflector and the bowl are removable intact from the lower end of the socket.

10. The combination of an electric lamp, a reflector, a light diffusing bowl below said reflector, a holder having a plurality of flexible resilient arms, said arms having hooked lower ends to detachably engage and support said bowl, so that the bowl can be removed by springing one of said arms outwardly from said flange, the upper ends of 20 said resilient arms being curved to engage the inner edge of said reflector to support the bowl therefrom, and a rigid ring attached to said arms to retain them in spaced relation, said reflector having a central open-

ing through which said ring may pass upwardly by flexing the lower ends of the arms toward each other. 45

11. The combination of an electric lamp, a reflector, a light diffusing bowl below said reflector, a holder having a plurality of flexible resilient arms, said arms having hooked lower ends to detachably engage and support said bowl, so that the bowl can be removed by springing one of said arms outwardly from said flange, the upper ends of 50 said arms being curved and disposed upwardly and outwardly over the inner edge of said reflector to support the bowl therefrom, and a rigid ring attached to and near the top of said arms and below the plane of 55 the inner edge of said reflector, said reflector having a central opening through which said ring may pass upwardly by flexing the lower ends of the arms toward each other. 60

12. The combination of an electric lamp 65 socket, a reflector having a central opening for the socket, a bowl below the lamp, supporting means for detachably engaging the rim of said reflector around said opening, so that the reflector is removable by downward 70 disconnection therefrom, supporting means for detachably engaging the rim of the bowl, and fastening means whereby said reflector and the supporting means therefor are removable intact from the lower end of 75 said lamp socket, the lower end of the supporting means for the bowl being adapted for insertion through said opening to engage or disengage the bowl.

13. A structure as specified in claim 12, 80 said means for supporting the bowl comprising spring arms which can be pressed together at their lower ends to pass through said opening.

In witness whereof, I have hereunto subscribed by name this 6th day of September, 1919.

HERBERT O. TOMLINSON.
